BOTTOM DUMP APPARATUS

Hugh W. Sanford, Knoxville, Tenn.

Application August 13, 1932, Serial No. 628,741

50 Claims. (Cl. 105—253)

This invention relates to improvements in apparatus having drop bottom doors which are released for dumping so that the contents of the apparatus may be discharged downward past such doors, and particularly to apparatus in which a plurality of such doors are held closed through the agency of a single latch mechanism, but can open at a dumping point in succession from the front rearward.

10 One of the features of the present invention is the provision of an apparatus having doors which may swing downward for an opening movement whereby material may pass such downwardly swung door, in conjunction with a movement at a right angle to the door axis whereby the door operates to free another door for the opening movement of the latter, together with devices whereby a closing movement of the door by upward swinging about its axis will likewise occasion a return movement of the door in a direction at a right angle to its axis whereby said devices are brought into position for supporting the other door.

Another feature of the present invention is the provision of a traveling apparatus having a plurality of doors adapted to swing about axes transverse to the line of movement of the apparatus, and in which at least one of said doors is permitted a movement forwardly and rearwardly with respect to the apparatus while it is swinging for opening and closing, in conjunction with door guides which cause a forward movement of the door as it moves toward closed position.

A further feature of the present invention is the provision of such door moving means as interengaging wedging or cam members on the door and frame.

Still another feature of the present invention is the construction of the door in which a simple door structure is provided adapted for pivotal swinging movement about a rod secured to the frame, the door being provided with means for permitting a sliding movement of the door with respect to said rod, so that the door may move in a direction at a right angle to the axis of the rod during its swinging movement, and thereby move from and to a securing relationship with respect to another door.

Still another feature of the present invention is the provision of an apparatus comprising a plurality of bottom doors of which at least one is supported pivotally on a pendulum-like member, and by its pivotal movement is adapted to open, and by the swinging movement of the pendulum-like member is adapted to enter into securing re-

lationship with respect to a door located more closely to the front of the apparatus: in some cases in conjunction with means operated by such forward door for rocking the pendulum-like member into its securing position as the forward door moves to its closed position.

Further features forming objects of the present invention are set forth in the following specification and claims, in conjunction with the illustrative forms on the accompanying drawings.

In these drawings:

Figure 1 is a vertical longitudinal section through a vehicle of the type mentioned, illustrated as a mine or industrial car, having two axles on its frame for supporting the wheels, and with doors located in front, between and behind these axles.

Fig. 2 is a corresponding view, on a larger scale, showing the relationship of a forward door and a rearward door, together with the devices for moving the rearward door into a forward position upon closing whereby it may secure the forward door against opening.

Fig. 3 is a similar view showing the rearward door in open position.

Fig. 4 is a vertical transverse section of a fragment of the structure, substantially on line 4—4 of Fig. 2.

Fig. 5 is a sectional view of a fragment, substantially on line 5—5 of Fig. 2.

Fig. 6 is a view corresponding to Fig. 1, but illustrating a modified form of door construction.

Fig. 7 is a detail view, on a larger scale, of a portion of Fig. 6.

Fig. 8 is a view corresponding to Figs. 1 and 6, but showing another modified form.

Fig. 9 is a view on an enlarged scale of the portion of Fig. 8.

Figs. 10, 11, 12 and 13 are fragmentary views corresponding to Fig. 1, and show further modified forms of door system.

Figs. 14 and 15 are fragmentary views, showing further modified forms of the door system.

Fig. 16 is a side elevation, showing the employment of the invention in a conveyer.

Fig. 17 is a fragmentary plan view of the operative flight of the same.

Fig. 18 is a transverse sectional view, showing the conveyer in conjunction with a loading device.

In the form shown in Figures 1 to 5 inclusive, the car is shown to have side sills 10 having upwardly extending body plates 11 and end plates 12. The axles 13 for wheels W are supported by suitable means (not shown) in the side sills 10,

and each is protected by an upwardly directed angle member 14 which has its longer leg extended toward the front of the car (to the right in Fig. 1) and operates to strengthen the construction and to protect the axles in part from the pressure of the lading. The front door 15 may be mounted by pivot members 16 fixed to the side sills 10, and extends from side to side of the car so that, in the closed position shown in Fig. 1, it serves to retain above it a corresponding portion of the lading in the car. The central door 17 and rear door 17a may be alike in shape and are each supported on transverse pivot rods 18 (Figs. 2, 3 and 5) located, beneath 15 the corresponding angle member 14, in the slots 19 of lug plates 20 which are secured to the transversely extending connecting piece 21 and thus to the pendulum members 22 which at their upper ends pass through apertures 23 in the angle members 14. The lower ledge 24 of a transverse angle member 21 engages beneath the rear edge of the next forward door 15 or 17 to hold the same against downward opening movement.

Each of the doors is illustrated as comprising 25 a single sheet of metal having an upturned stiffening lading-retaining flange at each edge, and being bent upwardly to provide an abutting nose 25 at its forward and upper edge. The transverse pivot rod 18 is illustrated as located above 30 this sheet, and securing and stiffening members 26 are fixedly secured to the door sheet, conform to the pivot rod 18, and at their forward upper portion closely join the nose 25. At the sides, the door sheet is provided with upwardly extending cam members 27 which engage with the rollers 28 mounted by fixed pivots 28a on the side sills 10. Pins 18x (Fig. 5) prevent endwise disengagement of the rods 18.

At the rear edge of the rear door 17, at the 40 rear end of the car, is provided some suitable latching means 30, for retaining the rear door in its raised and closed position.

In operation, the car is filled with lading, and is drawn over rails R to a discharge point at 45 which the latch 30 is tripped whereby to release the rear door 17 and permit it to swing downwardly about its pivot. In dropping down upon the ties, or upon the material already present at the discharge point, a frictional rearward 50 drag is exerted upon this rear door 17. As the door swings downward about its pivot 18, the nose 25 leaves the pendulum piece 22, and thereupon the weight present upon the middle door 17, the weight of the pendulum members and associated parts, and the frictional drag aforesaid, causes the pendulum members 22, the transverse piece 21, and its web 24 to swing in a clockwise direction (Fig. 2) toward the position shown in Fig. 3 in which the web 24 has released the middle 55 door 17. This middle door 17 therefore is free to drop about its pivot rod 18 and in turn and in like manner releases the front door 15. As each door opens, it swings about its pivot 18 or 16 and the rear and middle doors likewise may travel lengthwise with the pendulum members 22. By the provision of the slots 19 for the ends 60 of the pivot rods 18, however, as the nose 25 tends to move rearwardly away from the corresponding pendulum members 22, the latter are forced in a clockwise direction for the reasons aforesaid, and may rock independently of the rearward movement of the transverse rod 18, so that a quick opening of the door is attained, corresponding to a very small angular movement 65 about the axis of the pivot rod 18.

As the doors discharge and pass from the discharge point, they individually ultimately come to the position shown in Fig. 3. During the further transit of the car (toward the right in Fig. 1) each of the doors is brought against the closing device C which is located along the right of way, between the rails R, and thus the door is automatically raised into its closed position. For example, as the front door 15 is raised it is brought to the position of normal closure, and thereafter is held supported in such position by a horizontal portion H in extension of the device C. The middle door 17 is then raised by the device C until it likewise moves into closed position. During this movement, the door swings 15 around its pivot rod 18 until the nose 25 engages the pendulum members 22 and causes a counterclockwise movement of these members. During this portion of the movement, it is a matter of indifference as to whether the rods 18 are at the 20 forward or rearward end of the slots 19. Ultimately, as the middle door 17 approaches its closed position, the cam piece 25 engages roller 28 and thereby the middle door 17 is forced forward, and therewith the pendulum members 22 are swung in a counterclockwise direction until the web 24 engages beneath and secures the front door 15 against downward opening movement. By reason of the slots 19, this movement of the pendulum members 22 is assured, regardless of 30 whether the pivot rod 18 is in the front portion of the slots 19 or not. In this condition of the parts, it will be noted that so long as the middle door 17 is in its closed position, any tendency of the pendulum members 22 to move clockwise 35 is resisted by the nose 25 which is held in proper raised position by the engagement of the transverse rod 18 against the walls of the slots 19, and the nose 25 is likewise held against rearward movement by the engagement of cam 27 with rollers 28.

The middle door 17 is temporarily held in its closed position by the horizontal portion H in extension of the device C until the rear door 17a is likewise swung open into its closed position and engaged by a latch 30. A similar operation occurs at this rear door, so that the transverse web 24 on the pendulum members 22 of the rear door operates now to secure the middle door 17 in closed position.

Thus it will be seen that each door is individually moved to closed position by the device C, and then is latched during the closing of the next rearward door; and that each door in closing moves to the position in which it is to remain during transport of lading, so that the effort required for closing each door involves that of raising it and moving it forward into its proper closed position.

In the form of construction shown in Fig. 6, the side sills 10 and other parts are provided as before, and the front door 15a is carried by a fixed pivot 16a. The middle door 17b is formed of a metal sheet having lateral stiffening and lading supporting flanges, and at its forward edge is bent downwardly and rearwardly at 37 to provide an open loop which embraces the transverse pivot rod 18a located between the side sills 10 and resting in slots 38 of stiffening pieces 39 attached to the side sills. These stiffening pieces 39 are connected to the angle members 14a and have apertures 40 through which the car axles and their usual collars may be passed for insertion in or removal from the car. The rearward stiffening pieces 39 are provided on the lower portion of 75

their front edges with inclined surfaces 41 for engagement by the pieces 42 secured to the lateral flanges of the door sheet 17a.

At the rear of the car is provided a latch 43 with 5 a blocking member 43a for engaging and holding the rear edge of the rear door 17c in closed position. This rear door is likewise provided with pieces 42a for engagement during the final closing movement with the surfaces 41 on end 10 pieces 44.

In operation, with the front and middle doors in the position shown in Fig. 6, and the rear door swung to closed position and secured by latch 43, the car may support its lading and be transported 15 over rails R to the discharge point, at which the latch 43 is released. By this release of the latch, the rearward door 17c is free to swing downward as before, and by the frictional drag aforementioned and also by its weight, it also slides along 20 rod 18a rearward relative to the side sills and passes from the position shown in Fig. 7 into that shown in Fig. 6. This combined swinging and sliding movement quickly releases the rear edge of 25 the middle door 17b which has theretofore been supported upon the rear door 17c so that the latter in turn may swing downward and move relatively rearward and in turn release the front door 15a. With a dump car, for example, all 30 doors may be thus released before the front door arrives at an empty part of the discharge bin. The doors thereupon discharge their lading in 1-2-3 order, and the front door is not held closed until its lading must fall a great distance to the bottom of the bin. The discharge of the lading 35 thus occurs. Each door is then engaged by the closing device C and raised into closed position as before, being momentarily held therein by the horizontal member H in extension of the closing device C. As a middle or rear door is moved to its 40 closed position, it at first swings around its pivot rod 18a until its pieces 42 engage corresponding surfaces 41, whereupon a further raising movement causes a forward movement of the corresponding door into its normal holding relationship with the next forward door (respectively the front door 15a and the middle door 17b in Fig. 6). In this form, also, this movement occurs independently of the closing of any other door. When 45 finally the rear door 17c is raised, it in turn is moved forwardly to hold the middle door 17b in secured position and is itself latched by the latch 43. The car is then ready for further transport of lading. Each bodily movable door is held 50 in its forward bodily moved position by an element fixed to the frame and engaging the door adjacent its rear edge.

In the particular form of construction shown in Figs. 6 and 7, it will be noted that the parts are so arranged that the doors, axles and pivot rods 55 may be removed without disassembly of the fixed parts of the frame and body. The axles for example may be removed by raising the body until an axle 13a is centered with the corresponding holes 40 in the stiffening pieces 39 in the side sills 60 10, one wheel is removed, and then the axle and its collars may be slid transversely out of the car. The door and its pivot 18a may then be slid upwardly and rearwardly along the slots 38, and then the rod 18a drawn transversely out of the car, whereupon the door is free. It is also, however, 65 possible to remove a door without first removing the corresponding axle and pivot rod 18a. As shown in Fig. 7, it is possible, at any place where there is freedom between the rails for a door to swing freely, to rock a door such as 17b in a counter-

clockwise direction about its pivot rod 18a into the position shown in dotted lines in Fig. 7, raising the next forward door to permit this movement if necessary, and then sliding the door which is to be removed in a rearward direction until its end 37 clears the pivot rod 18a, whereupon the door drops free from the car. Thus it is easy to replace axles, pivot rods and doors if these become damaged or worn. 5

In the form of execution in Figs. 8 and 9, the 10 axles 13b extend as before through the side sills 10. Each of these axles is provided, adjacent the side sills 10, with the pendulum members 22a which are provided with arcuate slots 45 for receiving the fixed stops 46 on the side sills 10. At 15 the lower end of each pair of pendulum members is provided a transverse pivot rod 18b for the corresponding door. The front door 15b is mounted on the fixed pivot 16b. The middle and rear doors 17d, 17e are mounted on the transverse rods 18b. 20 A latch 43b is provided to receive and secure the rear edge of the rear door 17e.

In operation, this form of construction, with the bottom doors closed and the bodily movable doors held in forward position, upon the release 25 of latch 43b, permits a dropping of the rear door 17e, and therewith the frictional rearward dragging effect upon the door as before, assisted by the pressure of the middle door 19d and its lading, causes a clockwise movement of the rear pendulum members 22a. This in turn results in a dropping of the middle door 17d, and in sequence a rocking of the forward pendulum means 22a so that the front door 15b may drop. Normally, all 30 doors are thus released before the front door 35 passes over the discharge bin, so that each successive door opens fully only as it comes to an empty part of the bin. When the load has been discharged, the car in its passage over the track side car member C and the extension H causes 40 a raising of the front door 15b into closed position (Fig. 8) where it is held at least until the middle door 17d has also been raised. In the form of construction shown, the engagement of the camming noses at the rear edges of the side 45 flanges of the front door 15b with the wedging or forcing surfaces provided at the front edges of the pendulum means, causes a counterclockwise rocking of the pendulum and therewith a bodily forward movement of the middle door 17d, 50 until the front edge of this middle door 17d engages beneath the front door and holds the latter against later dropping. As the middle door 17d is raised on contact with the closing device C, it may also engage with a similar wedging or forcing surface provided on the rear pendulum means 22a whereby also to produce a forward movement of the middle door 17d, and also to occasion a counterclockwise movement of the rear pendulum means 22a for moving the rear door 60 17e bodily forward, so that this rear door may then retain the middle door 17d in closed position. Finally, the rear door is latched by the device 43b in usual manner. 55

In the form shown in Fig. 10 the axles 13c are 65 mounted as before with respect to side sills 10. Over each axle fits a pendulum piece 22b which has a curled upper or rearward end adapted to fit the corresponding axle and to move concentrically about it. The forward door 15c is mounted on a fixed pivot 16c. The middle door 17f and the rear door 17g are each provided with upwardly and rearwardly rebent portions which closely embrace the transverse rods 18c. In this 70 form of construction, there are provided for en- 75

agement with the rear edges of the middle and rear doors the wedging or forcing pieces 44c, 44d which operate to force the corresponding doors forward during their closing movement. The 5 forcing piece 44c is shown as connected to a side sill 10 and as being provided with an upwardly and forwardly inclined slot in which the rear rod 18c may move. A piece 44x adjacent the forward axle is provided with a similar slot for 10 the forward rod 18c.

In operation, the structure according to Fig. 10 may be loaded with its doors in closed position and the rearward door 17g held by a latch 43c. Upon arriving at a dumping point, this latch is 15 released and thus the rear door 17g is permitted to drop and move rearward, its rod 18c sliding downward and backward in the corresponding slots of the pieces 44c until the rod attains the position shown in 18c, being assisted in this 20 movement by friction as before, and by inclination of the slot itself. This movement withdraws the rod and door portion from its former position, in which these were in supporting relationship to the pendulum pieces 22b, and thus the piece 25 moves to the position shown adjacent the rear axle in Fig. 10, so that the middle door 17f may now likewise drop and make a rearward movement whereby to release the pendulum piece 22b at its forward edge, and thus in turn release the forward door 15c. After discharging the lading, the forward door 15c encounters a closing device C as before, and is swung into its closed position about its fixed pivot 16c. A moment later, the 30 middle door 17f is likewise swung toward its closed position by the same closing device, and in its closing movement encounters the forcing surface of the piece 44c and is thus moved forwardly so that the rod 18c thereof travels forwardly and upwardly in the corresponding slots 35 and pushes the corresponding pendulum piece 22b into holding engagement with the rear edge of the forward door 15c. In turn, the rearward door 17g is moved into closed position, being forced forward by the forcing surface of the piece 44d, so that it also presses its corresponding pendulum piece 22b into holding engagement with the middle door 17f, and is itself latched by the 40 latch 43c. During these operations the respective doors have been closed by the horizontal extension H of the closing device C. After the latch 43c operates, the car may be returned to the mine or other point for reloading.

In the form of construction shown in Fig. 11 55 the side sills 10 are mounted with respect to the axles 13d, and in the illustrated form each axle has an angle iron 14b extending across the same and serving as a support from which are suspended the pendulum pieces 22c having the ledges 24c for engaging the corresponding doors. The front door 15d is mounted on a fixed pivot 16d. The middle door 17h is mounted by pivot connections 18d to the corresponding pendulum pieces 22c and their ledge 24c. The rear door 17i is similarly mounted by a pivot 18d. A forcing piece 44e is attached to the frame adjacent the rear axle and is provided with a forcing surface for moving the middle door 17h forward as it closes. A forcing piece 44f near the rear end 60 of the car performs a similar function for the rear door 17i.

The method of operation is the same as described above, in conjunction with the latch 43d for the rear door. In this form of construction it 65 is preferred to provide the fixed stops 60 on the

frame for limiting the rearward movement of the pendulum pieces 22c.

In the form of execution according to Fig. 12 70 the side sills 10 are mounted with respect to the axles 13e which are illustrated as having bearing members 13x of semicircular external shape above them. The front door 15e is mounted on a fixed pivot 16e. The middle door 17k has its forward edge bent upwardly and backwardly, so that it fits over the front axle and also the bearing members 13x. A spacer member 13y holds the free edge of the door structure in proper position, and prevents separation of the door from the axle. The rear door 17l is similarly mounted upon the rear axle 13e. The frame supported 15 member 44g has a surface for forcing the middle door forward as it moves to closed position, and a similar piece 44h is provided at the rear end of the car for the rearward door 17l. Mounted on the middle and rearward doors, adjacent the 20 rebent portions thereof, are the securing pieces 61, which in the closed position of the doors serve to support each the next forward door.

The operation of this door system during discharging and relatching is substantially the same 25 as before. Each door is closed and brought to its final lading-holding position before the door located to its rear is brought into lading-holding position. When all doors are finally returned to the lading-holding position, a latch 43e may 30 operate to hold the rear door, and each door then operates to secure the door in front of it in proper position ready for immediate discharge.

In the form of construction shown in Fig. 13, 35 the doors are substantially of the type shown in Fig. 12, except that the supporting members 61 are omitted. In lieu thereof, the transverse rods 18f support pendulum pieces 22f which have ledges 24f at their lower edges to support the 40 next forward door. Each sliding door in this instance operates substantially in the manner already described in Fig. 10.

In the form of construction shown in Fig. 14 45 the front door 15m is mounted on a fixed axis 16m. The middle door 17m and the rear door 17n have rebent front edges of the form shown in Figures 6 and 7 which fit over the transverse supporting rods 13m which may be the axles of the vehicle. These doors therefore have both the swinging and the sliding movement as described for the form of construction shown in Figures 6 and 7. The structure of the rear door 17n includes filler pieces 17x which are of wedge-shape and extend, when the door is being dragged along a bottom drag rail RX after dumping, to 55 present a surface for engagement by the rear edge of the middle door 17m as the latter is swung upward toward closed position by the closing device C as before. Above the filler pieces 17x is a stop 39x on the apparatus frame. In 60 operation, the doors are released for dumping as described before, by the release of the latch 43m. As the front door 15m strikes the closing device C, it is swung upward into the position shown in Figure 14. As the middle door 17m encounters the closing device, it is likewise swung upwardly, but during its closing movement encounters the forwardly presented surface of the open rear door 17n and thereby is given a forward bodily movement relative to the frame of the apparatus 65 so that it successively moves into the positions shown in dotted lines in Fig. 14. It will be noted that the surface of the filler pieces 17x permits a smooth transfer of the rear edge of door 17m from the filler piece to the stop 39x. When the 70 75

rear edge of door 17m rests against stop 39x, it is in engaging position with the forward door 15m and thus prevents opening of this door; and it itself is held in closed and forwardly moved position by the fixed stop 39x. As the rear door 17m encounters the closing device C, it in turn is swung upwardly about its pivot and by encountering the cam surface 41m is moved bodily forward and into holding relationship beneath the middle door 17m (dotted lines, Fig. 14). The latch 43m is re-engaged to hold the doors in closed position.

In the form shown in Fig. 15, the forward door 15p is mounted on a fixed axis 16m for swinging movement. The middle and rear doors 17p, 17q are provided at their forward edges with members which are rebent into U-shape, the axis of the U portion being directed at a considerable angle to the general extension of the lading-receiving portion of the corresponding door. A fixed stop 62 is provided for holding the middle door 17p in relatively forwardly moved position when closed, and the latch 43p likewise secures the rearward door when closed in a closed and forwardly moved position. In operation, release of the latch 43p permits downward swinging and bodily rearward movement successively of the rear door 17q and the middle door 17p whereby the middle door and front door are released for dumping movement. After dumping, the front door 15p encounters the closing device C as before and is moved to the closed position shown in Fig. 15. As the middle door 17p encounters the closing device, it is given a bodily movement relative to the frame, substantially in the direction of the U-channel (arrow, Fig. 15), so that the door is raised from its former position in which the pivot 13p thereof was engaged at the bight of the U portion into the position shown in full lines in Fig. 15. Further movement of the apparatus relative to the closing device C causes a swinging of the middle door 17p from the position shown in full lines into that shown in dotted lines, in which it presents the bight of the U portion beneath the rear edge of the forward door 15p to hold the latter closed. The rear door 17q is shown in full lines in its fully opened position with the bight of its U portion resting upon the corresponding pivot 13p. As it encounters the closing device C, it also is moved bodily and swung into the closed dotted line position of Fig. 15, where it in turn presents its U portion beneath the rear edge of the middle door 17p to hold the latter closed and in engagement with the stop 62 which prevents any bodily movement of this door. Finally the rear door 17q is engaged by the latch 43p which prevents swinging or bodily movement of this door.

From the form of construction shown in Figures 16, 17 and 18 it will be noted that the door system is not limited to a dump vehicle having road or rail wheels, but that it may be employed in a conveyer system comprising an endless chain of drop-bottom doors.

The shaft 70 supports a sprocket wheel 71 which may engage with the wheels Wa and transfer these wheels from lower guide rails 73 to upper guide rails 74. While the wheels are engaged with the lower guide rails 73 they are moving in the conveying flight. The axles 74 of these wheels provide pivot rods for the connecting link members 75 and for the body sides 76 of the conveyer. Drop bottom doors 77, 78 and 79 are shown on the axles 74 corresponding in construction and arrangement with the drop

bottom doors of Figures 6 and 7. As the operative or lower flight of the conveyer moves toward the right in Figure 16, it conveys material contained between the body wheels 76 and upon the successive doors 77, 78 and 79. The doors are arranged in triplets in this construction, and the rear door 79 of each triplet is normally supported by a latch 80 pivoted to the body wall 76 adjacent the door 79. During the movement of the doors, the latch 80 encounters a fixed stop 81 which causes a relative clockwise movement of the latch and therewith a releasing of the door 79 which swings downward and moves bodily rearward as before, and thus releases the middle door 78 which in turn by swinging and bodily movement opens and releases the front door 77 of this triplet. The lading on the doors of this triplet thus is released for dumping. The closing device C operates upon the front door 77 to close it into the position shown in Fig. 16, and to hold it in this position temporarily. When the middle door 78 of the triplet encounters the closing device C, it is likewise swung upwardly and by encountering the forcing piece 82 is moved bodily forward until it presents its forward edge beneath the rear edge of the front door 77 and holds the latter in raised position. As the rear door 79 encounters the closing device C, it likewise is swung upwardly and by its encounter with the forcing piece 83 is moved bodily forward into a similar holding position beneath the rear edge of the middle door 78: toward the end of its closing movement it encounters the inclined surface of the latch 80 and swings the latter. As the rear door 79 reaches its closed position, the latch 80 swings back again and retains it against opening.

In the conveyer shown in these figures, the front door 77 is held by a roller 84 against downward dropping while in the upper or return flight. The middle door 78 is held by a nose 82a formed integral with the forcing piece 82. The rear door 79 is likewise prevented from such dropping movement during the return flight by an angle piece 85 which extends beyond the rear edge of the rear door 79 and serves, during the lower or operative flight, also to prevent the passage of lading between the rear door 79 of one triplet and the front door 77 of the next succeeding triplet.

In Fig. 18, a helical chute 86 is illustrated for conveying lading onto the operative lower flight.

It will be noted that in the several forms of construction, a plurality of doors are provided, each of the doors being independently pivoted, and interengaging means are provided so that each door maintains the next forward door in closed, i. e. upwardly swung, position: and that in many of the forms, independent devices are provided for each bodily movable door for holding it in forwardly moved position, and particularly that in several instances these devices are fixed to the frame of the apparatus and engaged with the particular door adjacent its rear edge. In such devices, the doors are held in forwardly moved position independently of the operation of the next rearward door for holding it closed so that little or no stress is transmitted from one door to another in the longitudinal direction of the vehicle for the purpose of holding a bodily movable door in forward position. By the provision of bodily movable doors, a single latch is enabled to control the system of doors, and upon release permits a dropping movement whereby the previously latched door is enabled to escape from the element which has previously been holding

- it in forwardly moved position. Thus each door releases the next forward door for dropping without itself having swung through any considerable angle. Hence the assembly of doors is released so that the doors of a mine car, for example, may fall upon the ties before the front door has come to an empty portion of the bin. The doors then open successively from the front rearward, as they move at an empty portion of the bin. No door 10 is then held in closed position so long that it has not opened until its lading must fall a considerable distance to the bottom of the bin. This arrangement, which may be called a 1-2-3 order of dumping for a three-door mine car, is of great 15 advantage in the handling of such lading as coal. In mine cars, the frame structures are preferably made very low and close to the rails, in order to permit a maximum capacity. In prior types of door controls, the rearward door was required to 20 move through a considerable angle before releasing the next forward door, etc.: and hence with a low frame, the release of the doors did not occur until the rear door cleared the pile of material in the bin, so that the front door in releasing 25 its load permitted the load to drop a considerable distance to the bottom of the bin; and in practice from 2 to 3 percent of the lump coal is saved by this 1-2-3 order of dumping, as the coal is laid on the pile very gently and there is practically no breakage. In particular, it will be noted that 30 the present arrangement permits the release of all doors even though the frame structure is low, by the time that the falling edge of the rear door has passed below the frame structure.
- 35 It is obvious that many other forms of construction may be employed, and that many changes may be made in the door systems, as well as in the other parts of the apparatus. While the structure has been described with respect to 40 three doors, it is obvious that any number may be employed. The forms illustrated set forth various ways of practicing the invention, but it is obvious that the invention is not limited solely thereto, but many changes may be made in construction without departing from the scope of the 45 appended claims.
- Having thus described the invention what I claim as new and desire to secure by Letters Patent, is:
- 50 1. A drop-bottom dump apparatus having a traveling frame, a forward door and a rearward door, parallel pivot mountings for connecting the frame and said doors whereby each door may swing downward at its rear edge for opening, said rearward door when in closed position operating as an abutment means for preventing the opening of the forward door, means rigidly secured to the frame for holding said rearward door in forwardly shifted position when closed, said pivot mounting for said rearward door permitting it to shift rearward relative to the frame after a short initial downward opening movement of its rearward edge below said holding means, said shifting being independent of the continued opening movement of the door whereby to free the forward door for opening upon a limited downward movement of said rearward edge of the rearward door, and means for retaining said rearward door in closed position.
- 55 2. A drop-bottom dump apparatus having a traveling frame, a forward door and a rearward door, parallel pivot mountings for connecting the frame and said doors whereby each door may swing downward at its rear edge for opening, said rearward door when in closed position operating
- as an abutment means for preventing the opening of the forward door, means rigidly secured to the frame for producing a forward shifting movement of said rearward door while closing whereby it is restored when fully closed to position for holding the closed forward door in closed position, said pivot mounting for said rearward door permitting it to shift rearward relative to the frame after a short initial downward opening movement of its rearward edge below said holding means, said shifting being independent of the continued opening of the door whereby to free the forward door for opening upon a limited downward movement of said rearward edge of the rearward door, and means for retaining said rearward door in closed position.
- 60 3. A drop-bottom dump apparatus having a traveling frame, a forward and a rearward door, parallel pivot mountings for connecting the frame and said doors whereby each door may swing downward at its rearward edge for opening, said rearward door when in closed position operating as an abutment means for preventing the opening of the forward door, abutment means rigidly secured to the frame for direct engagement by a portion of the rearward door for shifting the rearward door forward during the last portion of its closing movement and for holding said rearward door forward while in its closed position, said pivot mounting for said rearward door permitting it to shift freely rearward relative to the frame independently of its opening movement after it has become disengaged from said abutment means, so that its rearward movement will free the forward door for opening, and means for retaining said rearward door in closed position.
- 65 4. A drop-bottom dump apparatus having a frame, a plurality of doors having transverse and longitudinally spaced pivot mountings relative to said frame whereby each door may swing downward at its rear edge for opening, the pivot mounting of an intermediate door being constructed and arranged to permit said door to shift forwardly and rearwardly relative to said frame, abutment means rigidly secured to said frame and intermediate door for shifting said intermediate door bodily forward relative to the frame during the last portion of the closing movement thereof, said intermediate door being operated in closed and forwardly moved position to secure the next forward door in closed position, said intermediate door being free to shift rearward relative to the frame independently of its opening movement after it has become disengaged from said abutment means, means operated by the closing of the door next rearward of said intermediate door for securing said intermediate door in closed and forwardly moved position, and means for retaining said next rearward door in its closed position.
- 70 5. A drop-bottom dump apparatus having a frame, a plurality of doors having transverse and longitudinally spaced pivot mountings including members fixed to said frame whereby each door may swing downward at its rearward edge for opening, the pivot mountings of two adjacent doors being constructed and arranged to permit said doors to shift relative to the frame connections of said members, independent means on said frame and each said door for shifting each said adjacent door bodily forward relative to the frame during the last portion of the closing movement thereof, each said door being free for forward bodily movement independent of
- 75

said means except during said last portion of its movement and the corresponding portion of the opening movement, the front one of said adjacent doors being operative in closed and forwardly moved position to hold the next forward door in closed position, means operated by the closing of said other adjacent door for securing said first adjacent door in closed and forwardly moved position, and means for retaining said other adjacent door in its closed position.

6. A drop-bottom dump apparatus having a frame; a forward door and a rearward door, parallel pivot mountings for connecting the frame and said doors whereby each door may swing downward at its rearward edge for opening, the pivot mounting of said rearward door permitting it to move bodily forward and rearward relative to said frame, said rearward door operating when in its closed and forwardly moved position for holding said forward door closed, means rigidly fixed to the frame against movement in the longitudinal direction thereof and engageable by said rearward door during the closing portion of the upward swinging and closing movement thereof for producing a forward bodily movement of said rearward door relative to the frame and for holding said rearward door in said forwardly moved position, said rearward door being free of said rigid means except during said last portion of its closing movement and the corresponding portion of the opening movement, and means for retaining said rearward door in its closed position.

7. A drop-bottom dump apparatus having side frame members, a transverse member extending across said side frame members, a forward door pivotally mounted at its front end for swinging movement relative to said side frame members, a rearward door located between said side frame members and having a rearwardly bent hooked portion at its front end engaged around said transverse member whereby said rearward door may swing and shift relative to said side frame members, both said doors being adapted to swing downward about their mountings for opening, means for shifting the rearward door relative to the side frame members during the forward swinging movement for closing of the rearward door whereby the rearward door may operate to secure the forward door in closed position and engaged with said rearward door only during the last portion of the closing movement thereof and during the corresponding portion of the opening movement and while the door is closed, and means for retaining said rearward door in its closed and forwardly moved position.

8. An apparatus as in claim 7 in which said rearward door has the hook portion downwardly and rearwardly re-bent, and said transverse member and associated car structure is so constructed and arranged that said rearward door cannot be disengaged from said transverse member while the door is in open or closed position or any position therebetween, and whereby said rearward door may be swung about said transverse member into a substantially up-side-down position, so that it may be slid along said transverse member and thereby disengaged therefrom and removed from the apparatus.

9. An apparatus as in claim 7 including means on said side frame members for limiting the shifting movement of said rearward door when in closed and normal open positions, and wherein said rearward door is located between the side sills so that it may be swung about said trans-

verse member into a substantially up-side-down position for sliding movement rearwardly relative to said side frame members whereby it may be disengaged from the frame and removed from the apparatus without hindrance by said limiting means.

10. A drop-bottom dump apparatus having side frame members, a transverse member extending between said side frame members, a forward door pivotally mounted at its front end for swinging movement relative to said side frame members, a rearward door located between said side frame members and having a downwardly and rearwardly bent hooked portion at its front end engaged around said transverse member to provide a mounting for swinging and shifting movement of said rearward door relative to the side frame members, said doors being adapted to swing downwardly at their rear edges about their mountings for opening, means for shifting the rearward door forward relative to the side frame members during the swinging closing movement of the rearward door whereby it operates to secure the forward door in closed position, and means for retaining said rearward door in its closed and forwardly moved position.

11. A drop-bottom dump apparatus having a frame, a forward door and a rearward door, said rearward door having its front edge rebent to provide a channel parallel pivot mountings on the frame for said doors whereby each may swing downward at its rearward edge for opening, said rearward door having its channel engaged over its pivot mountings whereby the door may shift relative to its said pivot mounting, said rearward door when in closed and forwardly shifted position operating to secure said forward door in closed position, and means for retaining said rearward door in its closed and forwardly shifted position.

12. A drop-bottom dump apparatus having a frame, a forward door, a rearward door, a pivot mounting on the frame for said forward door whereby it may swing downward at its rear edge for opening, pendulum means pivoted to the frame and to the rearward door for permitting said rearward door to swing downward for opening and also to move bodily forward and rearward relative to said frame, the said rearward door serving as an abutment means for holding said forward door closed when said rearward door is in its closed and forwardly moved position, interengaging wedging devices fixed rigidly to said frame and said rearward door for moving the rearward door bodily forward relative to the frame during its closing movement, and means for retaining said rearward door in its closed and forwardly moved position.

13. A drop-bottom dump apparatus having a frame, a forward door and a rearward door, a pivot mounting on the frame for said forward door whereby it may swing downward at its rear edge for opening, pendulum means pivoted to the frame and to the rearward door for permitting said rearward door to swing downward at its rear edge for opening and also to move bodily forward and rearward relative to said frame, said rearward door operating when in its closed and forwardly moved position for holding said forward door closed, said rearward door interengaging with the frame during its upward swinging movement of closing for producing a forward bodily movement of said rearward door relative to the frame, and means for retaining said rearward door in its closed and forwardly moved position.

14. A drop-bottom dump apparatus having a

- frame, a forward door and a rearward door, a pivot mounting on the frame for said forward door whereby it may swing downward at its rear edge for opening, pendulum means pivoted for movement relative to the frame and having a pivot connection to the rearward door for permitting said rearward door to swing downward at its rear edge for opening and to move bodily forward and rearward relative to said frame, said doors being interengageable when in closed position so that the rearward door may hold said forward door in closed position, and cooperating door-actuating elements secured to said frame and rearward door for interengagement during upward swinging movement for closing of said rearward door whereby to move said rearward door bodily forward relative to the frame, and means for retaining said rearward door in its closed and forwardly moved position.

15. A drop-bottom dump vehicle having a frame, a transverse axle extending across said frame, a transverse member extending across said frame and providing a diverting wall above said axle, a pendulum device pivotally mounted at the forward edge of said member, a rearward door pivotally mounted on said pendulum device for downward swinging movement at its rear edge for opening and adapted to move bodily with said pendulum device in the longitudinal direction of the vehicle, a forward door pivotally mounted on said frame and adapted to swing downward at its rear edge for opening, said rearward door when in closed and forwardly moved position providing an abutment for preventing the opening of said forward door, said rearward door being moved from abutment position by its opening and rearward movement, and means for retaining said rearward door in its closed and forwardly moved position.

20. 16. A vehicle as in claim 15 in which the pendulum device includes means for supporting the forward door in closed position, and in which said rearward door when retained in its closed and forwardly moved position constitutes an abutment for holding said pendulum in supporting position.

25. 17. A vehicle as in claim 15 in which said retaining means includes interengaging portions of the frame and rearward door for producing a bodily forward movement of said rearward door during closing, and operating in the closed position of said door to prevent rearward movement thereof.

30. 18. A vehicle as in claim 15 in which said retaining means includes interengaging devices on the frame and rearward door for producing a bodily forward movement of the rearward door during closing, said means on the door being located forwardly of the rear edge of the door.

35. 19. A vehicle as in claim 15, in which said pendulum device has a pin and slot connection with the rearward door for permitting the swinging and bodily movement thereof, and interengaging means are provided on the frame and rearward door for producing a forward movement of the door during closing.

40. 20. A drop-bottom dump vehicle having a frame, an axle extending transversely of the frame, an angle member extending across the frame above said axle and providing a diverting ridge thereover, a rearward door pendulum means pivotally mounted at the forward edge of said angle member and having a pin and slot connection located beneath said ridge for supporting said rearward door, whereby the rearward door may swing downward for opening, interengaging means on said door and said frame and located beneath said ridge for producing a bodily forward movement of the door during closing, means on the door for engaging said pendulum means and producing a positive forward rocking movement of said pendulum means during the forward movement of said rearward door, a forward door pivotally mounted on the frame for downward movement at its rear edge for opening, said forward door being retained in closed position by said pendulum means when the latter is in its forwardly moved position and being free to swing downward when said pendulum means is in a rearward position, and means for retaining said rearward door in its closed and forwardly moved position.

45. 21. A vehicle as in claim 20, in which said pendulum means has a pin and slot connection with the rearward door for permitting the swinging and body movement thereof, and interengaging means are provided on the frame and rearward door for producing a forward movement of the door during closing, and means are provided on said rearward door below said ridge for engaging said link means to produce a forward rocking movement thereof during the forward movement of the door.

50. 22. A drop-bottom dump apparatus including a frame and front, middle and rear doors having pivotal support members adjacent their front ends, means connected to the frame for supporting and permitting the middle door to swing downward at its rear edge for opening and also permitting forward and rearward bodily movement of the door relative to the frame, means rigid with the frame and interengaging means associated with said middle door whereby said middle door is forced bodily forward relative to the frame during the last portion of its closing movement, means controlled by said middle door for securing said front door in its raised position when said middle door is in its forwardly moved position, means controlled by said rearward door for securing said middle door in its closed and forwardly moved position when said rearward door is closed, said middle door being free for rearward bodily movement during the opening after release of said interengaging means from said frame means, and means for holding said rear door in closed position.

55. 23. An apparatus as in claim 22, in which said interengaging means on the frame and middle door comprises a device fixed to the frame, and a cooperating device rigidly located on said middle door forwardly of its rear edge when closed.

60. 24. A drop-bottom dump apparatus including a frame and front, middle and rear doors having pivotal supporting members adjacent their front ends, said middle door including stiffening flanges at its sides, means connected to the frame for supporting and permitting the middle door to swing downward at its rear edge for opening and also permitting forward and rearward bodily movements of the door relative to the frame, interengaging means associated with the frame and middle door and including means fixed to the frame and cooperating devices located on said flanges of the middle door for engagement with said fixed means during the closing movement of the door for producing a bodily forward movement thereof, interengaging means included in said front and middle doors for securing said front door in its raised position when said middle door is in its forwardly moved position, means con-

trolled by said rearward door for securing said middle door in its closed and forwardly moved position when said rear door is closed, and means for holding said rear door in closed position.

5 25. A drop-bottom dump apparatus including a frame and front, middle and rear doors having pivotal supporting members adjacent their front ends, said middle door including stiffening flanges at its sides, means connected to the frame 5 for supporting and permitting the middle door to swing downward at its rear edge for opening and also permitting forward and rearward bodily movements of the door relative to the frame, interengaging means associated with the frame 10 and middle door and including means fixed to the frame forwardly of the portion of the middle door when closed whereby said middle door is forced bodily forward relative to the frame during the closing movement and cooperating devices located on said flanges of the middle door 15 forwardly of the rear edge of the middle door when in closed position for engagement with said fixed means during the closing movement of the door for producing a bodily forward movement thereof, interengaging means included in said front and middle doors for securing said front door in its raised position when said middle door is in its forwardly moved position, means controlled by said rearward door for securing 20 said middle door in its closed and forwardly moved position when said rear door is closed, and means for holding said rear door in closed position.

25 26. An apparatus as in claim 22, in which said frame means includes a device rigid with the frame, and said engaging means on the middle door includes means engaging and moving in contact with said rigid devices during only the last portion of the closing movement thereof 30 whereby to produce said bodily forward movement of said middle door, said device and engaging means being free of one another except during said last portion of the closing movement and the corresponding portion of the opening movement.

35 27. An apparatus as in claim 22, in which said frame means includes a device rigid with the frame and located adjacent the pivotal supporting member of the middle door, and said engaging means on the middle door includes means engaging and moving in contact with said rigid devices during only the last portion of the closing movement thereof whereby to produce said bodily forward movement of said middle door, 40 said device and engaging means being free of one another except during said last portion of the closing movement and the corresponding portion of the opening movement.

45 28. A drop-bottom dump apparatus including a frame and front, middle and rear drop-bottom doors, interengaging means on the frame and said doors for permitting them individually to swing downward at their rear edges for opening and also permitting bodily movement of the middle and rear doors in the longitudinal direction of the frame, interengaging means on said doors whereby said middle door supports said front door when said middle door is in forwardly moved position and whereby said rear door supports said middle door when said rear door is in forwardly moved position, interengaging means on said frame and said middle and rear doors for effecting a bodily forward movement of each said door during only the last portion of its closing movement, said interengaging means permitting free-

dom of relative bodily movement of said doors and frame except during said last portion of the closing movement and the corresponding portion of the opening movement thereof, and means for retaining said rear door in closed and forwardly moved position.

5 29. A drop-bottom dump apparatus including a frame and front, middle and rear drop-bottom doors, interengaging means on said frame and doors for permitting them to swing downward at their rear edges for opening, and also permitting limited forward and rearward bodily movements of the middle and rear doors relative to the frame, individual means carried by the frame for engaging said middle and rear doors during only the last portions of their individual closing movements whereby to produce a bodily forward movement of the corresponding door relative to the frame and permitting freedom of relative bodily movement of said doors and frame except during said last portion of the closing movement and the corresponding portion of the opening movement thereof, and interengaging means on said front and middle doors for supporting the front door in closed position when said middle door is in closed and forwardly moved position, interengaging means on said middle and rear doors for holding said middle door in closed and forwardly moved position when said rear door is in its closed and forwardly moved position, and means for retaining said rear door in closed and forwardly moved position.

30 30. A drop-bottom dump apparatus comprising a lading body having a frame and an open bottom, a front door and a pivot mounting therefor on said frame, a plurality of rearward doors and pivot mountings therefor on said frame whereby the rearward doors may swing and also move bodily forward and rearward with respect to said frame, said doors when in closed position serving to close the body bottom and being each adapted to swing downward at its rear edge to discharge the lading carried thereabove, and independent means on each of said rearward doors and on the frame for engaging and moving each door bodily forward relative to the frame during only the last portion of its closing movement, each said rearward door when in closed and forwardly moved position operating to hold the next forward door closed.

35 31. A drop-bottom dump apparatus comprising a lading body having a frame and an open bottom, a front door and a pivot mounting therefor on said frame, a plurality of rearward doors and pivot mountings therefor on said frame whereby the rearward doors may swing and also move bodily forward and rearward with respect to said frame, said doors when in closed position serving to close the body bottom and being each adapted to swing downward at its rear edge to 40 discharge the lading carried thereabove, and independent interengaging means on each of said rearward doors and on the frame for moving each door bodily forward relative to the frame during its own closing movement, each said rearward door when in closed and forwardly moved position operating to hold the next forward door closed, said interengaging means comprising for each rearward door a cam member and a cam engaging member, one of said members being 45 supported on the frame and the other on the door.

32. A drop-bottom dump apparatus comprising a lading body having a frame and an open bottom, a front door and a pivot mounting therefor on said frame, a plurality of rearward doors and 50

5 pivot mountings therefor on said frame whereby the rearward doors may swing and also move bodily forward and rearward with respect to said frame, said doors when in closed position serving 10 to close the body bottom and being each adapted to swing downward at its rear edge to discharge the lading carried thereabove, and independent interengaging means on each of said rearward doors and on the frame for moving each door 15 bodily forward relative to the frame during its own closing movement, each said rearward door when in closed and forwardly moved position operating to hold the next forward door closed, said interengaging means comprising for each rear- 20 ward door a cam member and a cam engaging member, said cam member being supported on the door and said cam engaging member on the frame.

20 33. A drop-bottom dump apparatus comprising a lading body having a frame and an open bottom, a front door and a pivot mounting therefor on said frame, a plurality of rearward doors and pivot mountings therefor on said frame whereby the rearward doors may swing and also move 25 bodily forward and rearward with respect to said frame, said doors when in closed position serving to close the body bottom and being each adapted to swing downward at its rear edge to discharge the lading carried thereabove, and independent interengaging means on each of said rearward doors and on the frame for moving each door bodily forward relative to the frame during its own closing movement, each said rearward door when in closed and forwardly moved position 30 operating to hold the next forward door closed, said interengaging means comprising for each rearward door a cam member and a cam engaging member, said cam member being supported on the frame and said cam engaging member on the door.

30 34. A drop-bottom dump apparatus comprising a lading body having a frame and an open bottom, a front door and a pivot mounting therefor on said frame, a plurality of rearward doors and pivot mountings therefor on said frame whereby the rearward doors may swing and also move bodily forward and rearward with respect to said frame, said doors when in closed position serving to close the body bottom and being each adapted to swing downward at its rear edge to discharge the lading carried thereabove, and independent interengaging means on each of said rearward doors and on the frame for moving each door bodily forward relative to the frame during its own closing movement, each said rearward door when in closed and forwardly moved position operating to hold the next forward door closed, said interengaging means comprising for each rearward door a cam member and a cam engaging member, said members being located adjacent the front edge of the closed door and supported one on said frame and the other on said door.

35 35. A drop-bottom dump apparatus comprising a lading body having a frame and an open bottom, a front door and a pivot mounting therefor on said frame, a plurality of rearward doors and pivot mountings therefor on said frame whereby the rearward doors may swing and also move bodily forward and rearward with respect to said frame, said doors when in closed position serving to close the body bottom and being each adapted to swing downward at its rear edge to discharge the lading carried thereabove, independent interengaging means on each of said rearward doors and on the frame for producing

5 a bodily forward movement of the corresponding door relative to the frame during its own closing movement, each said rearward door when in closed and forwardly moved position operating to hold the next forward door closed, door and frame elements of said inter-engaging means being released from one another upon a short swinging movement of the corresponding door toward open position so that such door may thereafter move bodily rearward independently of its swinging movement and quickly release the next forward door, and means for limiting the closing movement of the doors. 10

15 36. A drop-bottom dump apparatus comprising a lading body having a frame and an open bottom, a front door and a pivot mounting therefor on said frame, a plurality of rearward doors and pivot mountings therefor on said frame whereby the rearward doors may swing and also move bodily forward and rearward with respect to said frame, said doors when in closed position serving to close the body bottom and being each adapted to swing downward at its rear edge to discharge the lading carried thereabove, and independent interengaging means on each of said rearward doors and on the frame for moving each door bodily forward relative to the frame during its own closing movement, each said rearward door when in closed and forwardly moved position operating to hold the next forward door closed, and a plurality of means pivotally mounted with respect to the frame and each adapted to support a door against opening, each said means being operated by the forward movement of one door as it closes into position for holding the next forward door closed and being operated to release the corresponding door upon a short swinging movement thereof toward open position so that such door may thereupon move bodily rearward independently of its swinging movement and quickly release the next forward door. 30

35 37. A drop-bottom dump apparatus comprising a lading body having a frame and an open bottom, a front door and a pivot mounting therefor on said frame, a plurality of rearward doors each having a rebent forward edge, said frame including pivot means engaged with the rearward doors adjacent the rebent edges thereof whereby the rearward doors may swing and also slide bodily forward and rearward with respect to said frame, said doors when in closed position serving to close the body bottom and being each adapted to swing downward at its rear edge to discharge the lading carried thereabove, and independent interengaging means on each of said rearward doors and on the frame for producing a sliding of each door bodily forward relative to the frame during its own closing movement, each said rearward door when in closed and forwardly moved position operating to hold the next forward door closed. 50

55 38. A drop-bottom dump apparatus comprising a lading body having a frame and an open bottom, a front door and a pivot mounting therefor on said frame, a plurality of rearward doors each having its forward edge rebent to form a slot, pivot mountings on the frame engaged in said slots so that each rearward door may pivot about its mounting and may slide with respect thereto, said doors when in closed position serving to close the body bottom and being each adapted to swing downward at its rear edge to discharge the lading carried thereabove, and independent interengaging means on each of said rearward 70 doors. 75

doors and on the frame for moving each door bodily forward relative to the frame during its own closing movement, each said rearward door when in closed and forwardly moved position operating to hold the next forward door closed.

39. A drop-bottom dump apparatus comprising a frame having side sills, front and rear wheel supporting members extending transversely between said side sills, a door control piece located on said frame adjacent said rear member and having a forwardly and upwardly inclined surface; forward and rearward drop-bottom doors, said rearward door extending between said members, pivot mountings for said doors located adjacent their front edges, the mounting for said rearward door including means for permitting a bodily movement of such door in a longitudinal direction relative to the frame whereby it may move toward and from the forward door; means on said rearward door for engaging said control piece toward the end of its closing movement whereby a bodily forward movement of said rearward door is produced, and means operated by the forward movement of said rearward door for holding said forward door in closed position.

40. An apparatus as in claim 39, in which said control piece is provided at each side of the frame adjacent the rear member, and said rearward door has engaging means connected at each side adjacent its rear edge.

41. An apparatus as in claim 39, in which the control piece projects forward of the rear edge of the rearward door, and said engaging means terminates in front of said rear edge.

42. A drop-bottom dump apparatus including a frame having side members with transversely aligned apertures therein, transverse axles passing through said aligned apertures, door control pieces fixed to the frame adjacent the apertures, said pieces having open-ended slots therein, a transverse rod extending between said side members and located with its ends in said slots, a first door pivotally mounted on said transverse rod and including a rebent portion providing a hook for engaging said rod, said door cooperating with said axle to prevent normal removal of said rod from said slots, said door being movable into substantially an up-side-down position in which it may be disengaged from said rod, said axle being withdrawable transversely through said apertures whereby to permit the movement of said rod along said slots into alignment with said apertures so that it may be withdrawn transversely through said apertures, and a second door supported on said side members for a downward swinging movement for opening and a bodily movement relative to the side members, said door being engageable with said piece during its closing movement whereby to produce a bodily forward movement of such door.

43. In a drop-bottom dump apparatus, an open-bottom frame, transverse axles on said frame, a rearward drop-bottom door having its forward end rebent rearwardly to provide a hook for engaging over an axle whereby the door may swing and slide, a forward door having a pivotal mounting on the frame for downward movement at its rear edge, interengaging means whereby said rearward door in its forwardly moved position will support said forward door in its closed position, and means for moving said rearward door into its forwardly moved position during closing and for holding it in closed and forwardly moved position.

44. An apparatus as in claim 43, in which said

interengaging means includes a tie rod connected to said frame and extending transversely above the axle, pendulum means pivotally mounted on said tie rod and extending forwardly and downwardly past the axle for supporting the rear edge of the forward door, said pendulum means being engaged by the rearward door when in forwardly moved position and thereby held against releasing said forward door.

45. An apparatus as in claim 43, in which the walls of the door hook are inclined upwardly and forwardly when the door is closed, so that said door moving means produces an upward and forward movement of the front edge of the rearward door during closing.

46. A drop-bottom dump apparatus including an open-bottom frame, forward and rearward doors, pivotal connections between the doors and frame adjacent their front edges whereby the doors may swing downward for opening movement and for permitting individual bodily movements of said doors in the longitudinal direction of the frame, means rigidly fixed to the frame for engaging and producing a forward movement of the forward door during closing and for limiting the upward swinging movement of said forward door and for holding said forward door when closed in its forwardly moved position and for releasing said forward door upon a short downward swinging movement thereof so that said forward door is thereafter free to move bodily rearward relative to said frame independently of its further downward swinging movement, and interengaging means on the rearward door and the frame for limiting the rearward and opening movements of such rearward door.

47. A drop-bottom dump apparatus including an open bottom frame, forward and rearward doors, the rearward door having a downwardly and rearwardly open-ended hook at its front edge, pivotal connections between the doors and frame adjacent their front edges whereby the doors may swing downward for opening movement, said pivotal connections for the rearward door engaging in said hook thereof, said connections permitting the doors to swing downward for opening movement and permitting individual bodily movement of said doors in the longitudinal direction of the frame, means fixed to the frame for producing a forward movement of the forward door during closing and for limiting the upward swinging movement of said forward door and operating to prevent disengagement of said hook of the rearward door from said pivotal connection thereof, and interengaging means on the rearward door and frame for limiting the rearward and opening movement of said rearward door.

48. In a drop-bottom dump apparatus, a frame, a transverse member extending across the frame, a forward door pivotally mounted adjacent its front edge on said frame for swinging downward to open, a fixed stop on the frame for limiting the upward swinging movement of said forward door, a rearward door having its front edge rebent to engage over said transverse member whereby the rearward door may swing about the axis of said member and may slide on said member, means on the frame for producing a forward sliding movement of the rearward door during its closing, and means for limiting such sliding movement, said rearward door in its closed and forwardly slid position acting to prevent the opening movement of said forward door.

49. A traveling drop-bottom dump apparatus having a frame, a forward door having a rear-

wardly open channel at its forward edge, a pivot on the frame located in a rearward part of said channel when the forward door is closed, said pivot and channel permitting the forward door to swing down at its rear edge for dumping and permitting it to slide with respect to said pivot until the pivot engages the end wall of said channel adjacent the front edge of the forward door whereby the pivot and said end wall prevent disengagement of the door from the frame while open for dumping, said forward door being engageable with a device located along the route of the apparatus and cooperating therewith for the quick restoration during the early stages of closing of said forward door to its closed and forwardly moved position with said pivot at a rearward part of said channel, a rearward door, a pivot on said frame for engaging said rearward door adjacent the front edge thereof whereby the rearward door may swing down at its rear edge for dumping, said rearward door being engageable with said device after the latter has closed the forward door whereby to move the rearward door into closed position, means operated by said rearward door in moving into closed position for holding the forward door in closed position, and means for holding the rearward door in closed position.

50. A drop-bottom dump apparatus having a frame, a plate metal forward door having the

front edge of its structure rebent upwardly and backwardly to provide a channel, a pivot on the frame engaged in a rearward part of said channel when the forward door is closed, said pivot and channel permitting the forward door to swing down at its rear edge for dumping and permitting it to slide with respect to said pivot until the pivot engages the end wall of said channel whereby the pivot and said end wall prevent disengagement of the forward door from the frame while open for dumping, said forward door being engageable with a device located along the route of the apparatus and cooperating therewith for the quick restoration during the first part of the closing motion of said forward door to its closed and forwardly moved position with said pivot at a rearward part of said channel, a rearward door, a pivot on said frame for engaging said rearward door adjacent the front edge thereof whereby the rearward door may swing down at its rear edge for dumping, said rearward door being engageable with said device after the latter has closed the forward door whereby to move the rearward door into closed position, means operated by said rearward door in moving into closed position for holding the forward door in closed position, and means for holding the rearward door in closed position.

HUGH W. SANFORD.
